UNITED STATES PATENT OFFICE.

JULIUS J. MILLER, OF ST. JOSEPH, MICHIGAN, ASSIGNEE, BY MESNE ASSIGNMENTS, TO
WIREBOUNDS PATENTS COMPANY, OF KITTERY, MAINE, A CORPORATION OF MAINE.

WIRE-BOUND-BOX-BLANK MACHINE.

1,260,932.

Specification of Letters Patent. Patented Mar. 26, 1918.

Original application filed October 11, 1909, Serial No. 522,156. Patent No. 1,089,069, dated March 3, 1914.
Divided and this application filed October 26, 1911. Serial No. 656,969.

To all whom it may concern:

Be it known that I, JULIUS J. MILLER, a citizen of the United States of America, and resident of St. Joseph, Berrien county, Michigan, have invented a certain new and useful Improvement in Wire-Bound-Box-Blank Machines, of which the following is a specification.

This is a division of my application Serial Number 522,156, filed October 11, 1909, for improvement in box blank machines granted March 3, 1914, as Patent No. 1,089,069.

My invention relates to improvements in machinery for making wire bound box blanks of that particular kind in which the different sections of the blank are flexibly connected together by a plurality of external binding wires which are held in place upon the veneer by the same staples that secure the reinforcing cleats to the inner surface of the blank.

Generally stated, the object of my invention is to provide a box blank machine having novel and effective means for spacing the cleats apart endwise, and for separating or spacing the edges of the veneer or other sheet material, whereby the sections of the blank are secured in proper relation to each other.

A special object is to provide a spacing device that enters between the edges of two adjacent sections of the blank to space the said edges the proper distance apart, and which is withdrawn from spacing position by means individual thereto, whereby the said spacing device travels a distance with the blank, withdraws therefrom, and then returns to again perform its spacing function, any suitable means, such as a cam and a spring, being employed for controlling the action of said spacing device.

Another object is to provide a spacing device that serves to separate the adjacent ends of two cleats, to produce the required space between the same, and which travels forward a distance with the blank in one direction, moves laterally a distance away from the path of the cleats, travels back along a path parallel with the said path of the cleats, and then moves toward the said path of the cleats, to assume a spacing position, all in

the same horizontal plane, whereby said spacing device is always right side up, and does not leave the said horizontal plane of movement.

It is also an object to provide certain details and novel combinations tending to produce a new mode of operation in a box blank machine of this character.

To the foregoing and other useful ends, my invention consists in matters hereinafter set forth and claimed.

In the accompanying drawings—

Figure 1 is a side elevation, with certain portions in section, of a wire bound box blank machine embodying the features of my invention.

Fig. 2 is a transverse section on line 2—2 in Fig. 1.

Fig. 3 is a horizontal section on line 3—3 in Fig. 1.

Fig. 4 is a detail perspective view of one of the links of one of the endless link belts shown in Figs. 1, 2 and 3.

Fig. 5 is a longitudinal detail side elevation of a series of the links shown in Fig. 4.

Fig. 6 is a plan view of the link belt construction shown in Fig. 5, illustrating the manner in which the spacing blocks travel along the angle irons or fixed guides that are provided for the cleats of the blanks.

Fig. 7 is an enlarged cross section on line 7—7 of Fig. 5.

Fig. 8 is an enlarged perspective of one of the spacing blocks shown in the preceding views.

Fig. 9 is a detail fragmentary view of a portion of one of the cleat guides shown in the preceding views, and of one of the inclined bars or strips by which the blanks are caused to rise from the guides, illustrating the manner in which the same are adjustable laterally for the purpose of varying the width of the blanks.

Fig. 10 is an enlarged detail perspective of that end of one of the cleat guides upon which the links of the link belt or chain have their initial movement in the general direction of travel of the blanks through the machine.

Fig. 11 is a perspective of one of the wire bound box blanks.

Fig. 12 is a detail fragmentary view of

one of the devices for adjusting the hubs of the sprocket wheels c and c' in the slots of the bars b and a' upon which they are carried.

- 5 As thus illustrated, my invention comprises a suitable frame or body A, upon which are mounted certain of the operative parts, said frame or body consisting of an upright casting at each side of the machine.
- 10 The upright castings B are disposed a suitable distance in advance of the castings from which the frame A is constructed, and are made adjustable by means of screws b . In this way the distance between the castings 15 A and B may be varied at will. The castings composing the frame A are connected by a bar a and also by another bar a' . The castings B are connected by a bar b . The bars a , a' , b are disposed in the same horizontal plane, and are thus adapted to provide a sort of table for the endless link belts C. These endless link belts are arranged to travel upon and around sprocket wheels c and c' mounted respectively upon bars b 20 and a' . It will be seen that these sprocket wheels have hubs which are adjustably mounted in slots b' and a^2 in the bars b and a' respectively. Thus the distance between these two endless link belts may be varied 25 at will, so as to vary the width of the wire bound box blanks. Any suitable device can be employed for positioning the said sprocket wheels at different points in the length of the slots b' and a^2 , as, for example, set 30 screws b^2 and a^3 .
- 35 Referring to Fig. 4, it will be seen that the links of the said endless link belts are each of the character shown in said figures, so far as the general form and construction 40 thereof is concerned. Each link has a flange c^2 provided with a longitudinal slot c^3 , which flange is at the outside of the belt or chain, as shown more clearly in Figs. 3 and 7. Fig. 4, more properly speaking, shows 45 only the upper member of one of the said links, the lower member c^4 being simply a straight bar. The upper and lower members of each link are spaced apart by the washers c^5 , it being understood that the pins 50 or pivots by which the links are connected extend through these washers. Thus the links are connected together by pins or pivots which serve as axles for the washers c^5 . These washers c^5 serve as anti-friction rollers, and are engaged by the teeth c of the 55 sprocket wheels. These endless link belts or chains which travel in horizontal planes, and which are operated by sprockets which rotate about vertical axes, are provided with spacing blocks D of the kind shown in Fig. 8. These spacing blocks may be of any suitable, known or approved shape, depending upon the formation desired for the ends of the cleats of the blanks. Each spacing block is 60 preferably provided with a threaded stud d ,

as shown more clearly in Figs. 7 and 8. The threaded studs d are inserted through the slots c^8 , and clamping nuts d' are then applied to them for the purpose of securely clamping the said spacing blocks at any desired point in the length of the links to which they are allotted. In this way each spacing block is adapted to be adjusted longitudinally of the link upon which it is mounted, whereby the distance between the spacing 70 blocks may be varied in accordance with the length of the cleats to be employed in the manufacture of the blanks. Each spacing block is also preferably provided at its top with a pin d^2 , which extends downward into the block, and which is controlled by a spring d^4 . These spacing blocks D are adapted to travel along the fixed guides E, which latter are in the nature of angle irons extending longitudinally of the machine, and 75 upon which guides the cleats of the blank travel endwise during the operation of stapling the veneer and cleats and binding wires together. The pins d^2 are so arranged 80 that their lower ends travel upon the flat horizontal surfaces of the said guides E, and are thus held in such position that their upper ends serve to separate the edges of the veneer—that is to say, the upper ends of 85 these pins d^2 extend upwardly between the edges of the several sheets of veneer comprised in each box blank, so that the said edges are spaced apart sufficiently to insure the desired result when the box blank is 90 folded around the rectangular end walls of 95 the box. When the spacing blocks D leave the forward ends of the guides E the pins 100 d^2 are thrust downward by the tension of the springs d^4 , whereby these pins do not project above the tops of the spacing blocks 105 while the latter are traveling back to the end of the machine where the materials are loaded thereon. In other words, the pins d^2 project above the tops of the blocks D 110 while they are traveling forward, and while they are performing their function of separating the edges of the veneer, but do not project above the tops of said blocks while they are traveling back to the place where 115 the operator is loading materials upon the machine. With reference to this mode of operation the ends of the guides E are provided with curved cams e upon which the spacing blocks D travel and which serve to 120 elevate the pins d^2 into position to cause the upper ends to project above the tops of the said blocks. At the other ends of the said guides E, and at that end of the machine where the blocks are stripped from the said guides, the cleats are adapted to ride up the 125 inclined surfaces of the bars or strippers F, which latter are secured to the bars a' . In this way the blanks are disengaged from the spacing blocks D before the links of the 130 chains start around the sprocket wheels c' .

It will be understood, of course, that before each spacing block D can be deflected from its longitudinal travel it must be fully disengaged from the cleats, for otherwise the spacing blocks would cramp or bind between the ends of the cleats. The strippers F, however, as stated, permit the blanks to rise from the guides E, and disengage themselves from the blocks D, before the links start around 5 the sprockets c' at that end of the machine where the blanks are delivered in finished condition. It is obvious that in order to secure this mode of operation the strippers F must be so proportioned and adjusted that 10 they engage the cleats of the blanks without engaging the spacing blocks D. Thus the cleats 1 of the blanks are caused to slide longitudinally along the guides E, by spacing blocks D interposed between the ends of the 15 cleats. The said guides E are adjustably mounted upon the bars a, a' and b, as for example by means of saddle blocks e' and set screws e² as shown in Figs. 9 and 10, whereby the distance between them may be varied 20 for the purpose of varying the width of the blanks.

Any suitable mechanism may be employed for operating the endless link belts C. For example, the sprocket wheels c', can be provided with vertical shafts which carry bevel gears G at the lower ends thereof, which bevel gears are adapted to engage similar bevel gears g on a horizontal shaft g'. This shaft, it will be understood, is supported in 35 suitable bearings on the frame A. Upon the said shaft is mounted a ratchet wheel g² that is actuated by a pair of dogs g³, which latter are carried by an arm g⁴ mounted to swing upon said shaft. This arm is operated by a rod g⁵, which rod is in turn operated by a lever g⁶ pivoted at g upon the base of the body of the machine. This lever g⁶ carries a roll g⁷ which is engaged and operated by a cam g⁸, which latter is mounted upon the main operating shaft g⁹. Thus the rotation of this shaft g⁹ serves to operate the feed mechanism consisting of the ratchet wheel g² and dog g³, whereby the endless link belts C are given a step-by-step feeding motion in the direction indicated by the arrows in Fig. 3. The mechanism is so arranged as to permit the lateral adjustment of the link belts C to accommodate different widths of blanks without interfering with the driving of the same. One suitable arrangement is illustrated in Fig. 2 wherein the shaft g' is provided with the rib g¹⁰ to permit the adjustment of the gears g along the same, the hubs of the gears being provided with set screws g¹¹ to retain them in adjusted position.

Any suitable stapling mechanism can be employed for driving the staples by which the binding wires are secured to the veneer and cleats. As shown in the drawings, four

staples H, H', H² and H³ are provided for this purpose, the said staplers consisting of upper and lower heads mounted upon the usual cross bars I and J. The bar J is rigidly mounted upon the side members of the frame A, while the bar I is reciprocated up and down by the rods or pitmen h at the rear end thereof. These rods or pitmen are operated by eccentric devices h', which latter consist of straps and cams carried by the shaft g⁹. The bar a is preferably provided with a pair of anvil blocks K, which blocks serve to clench the staples that secure the middle wires 2 upon the upper surface of the blank shown in Fig. 11. These staples 80 are driven by staplers H' and H², while the staples which secure the wires 3 to the side edges of the blanks are driven by the staplers H and H³. These staplers are all adjustable upon the bars I and J, which adjustment is necessary in view of the fact that the machine is adapted for the manufacture of box blanks of different widths. The staples which are driven crosswise of the wires 3 pass through the veneer and into the cleats 90 I, and do not pass entirely through the same. The staples which are driven crosswise of the wires 2 pass through the veneer 4 of the blanks and are clenched on the under surface thereof.

Any suitable means can be employed for feeding the binding wires 2 and 3, and for guiding the same below the different staplers, whereby the staples are driven crosswise thereof. In Fig. 1 such means are indicated conventionally by the wire-holding reels L. It will be understood that the movement of the blank with the wire secured thereto will draw the wire from the reel for application to the unsecured parts of the blank. 105 For clearness the reels have been omitted from the other figures. With the construction illustrated these binding wires are secured to the upper surfaces of the blanks, and are pulled along or fed forward by the 110 movement of the blanks through the machine.

Thus it will be seen that the pins d² are in the nature of spring fingers that are moved into and out of spacing position. 115 Each said finger is actuated in one direction by a cam, and in the other direction by a spring, whereby it moves into and out of the path of the sheets of veneer. As shown, the said cam is stationary and it is the forward movement of the finger against the cam that actuates the finger in the one direction. Also, it will be seen that the blocks D are in the nature of spacing devices that always remain right side up, and that never 125 leave the horizontal plane of movement, the forward and back movements of the said device being along parallel lines in the same horizontal plane. Thus the spacing device D has the peculiarity of being capable of 130

- spacing apart the ends of two cleats in the same wire bound blank, and of returning to starting position, without moving vertically, and without being turned up side 5 down. The fingers *d* having spacing and non-spacing positions on the traveling members *C*, and each finger is actuated to spacing position by a cam or stationary device *e*, and to non-spacing position by a spring *d*. 10 Each finger or spacing device is movable forward a distance with the blank, and then returnable in close proximity to the under surface of the blank. These spacing devices can be used in various ways, and for various 15 purposes, without departing from the spirit of my invention.
- I do not limit myself to the exact construction shown and described.
- What I claim as my invention is:
- 20 1. In a machine for making wire bound box blanks, the combination of guides for the cleats, endless traveling members provided with spacing blocks, whereby the cleats of each blank are spaced apart end- 25 wise, sprockets for said endless traveling members, said sprockets arranged to rotate about vertical axes, means for operating said members in a direction to cause the idle portions thereof to return under the blanks, 30 devices for stapling binding wires to the blanks, spacing devices on said blocks extending into the plane of the blanks, and means for preventing the said spacing devices while returning from interfering with the for- 35 wardly moving blanks.
2. A wire bound box blank machine in which the blanks have a step-by-step forward feeding motion, comprising means for applying the parallel binding wires, while 0 the blanks are moving along, mechanism for gaging or positioning the parts of the blank before said wires are applied, said mechanism comprising a spacing finger mounted to travel forward a distance between adj- 45 cent edges of two sections of the blank, movable into and out of spacing position, the said finger being returned to starting point along a path at one side of its path of forward movement, without interrupting the 50 said feeding motion, a spring for actuating the finger in one direction, and a cam for actuating the finger in the opposite direction.
3. A wire bound box blank machine in 55 which the blanks have a step-by-step forward feeding motion, comprising means for applying the parallel binding wires, while the blanks are moving along, mechanism for gaging or positioning the parts of the 60 blank before the said wires are applied, said mechanism comprising a movable member, a finger carried by and having spacing and non-spacing positions on said member, which finger is adapted to engage between 65 the edges of adjacent sections of the blank,
- to space the said sections apart, a spring for actuating the finger to one position, and a cam for actuating the finger to the other position.
4. A wire-bound box blank machine in 70 which the blanks have a step-by-step forward feeding motion, comprising means for applying the parallel binding wires while the blanks are moving along, a cleat guide, mechanism for gaging or positioning the 75 parts of the blanks before the said wires are applied, said mechanism comprising a member mounted for movement along the said guide, between adjacent portions of the same blank, a spacing finger carried by and having spacing and non-spacing postions on 80 said member, operated independently of control by any space in the blank ahead thereof, and means for actuating the said finger from one position to the other, the said finger being returned to starting point along a path at one side of its path of forward movement, without interrupting the said feeding motion.
5. A wire bound box blank machine in 90 which the blanks have a step-by-step forward feeding motion, comprising means for applying the parallel binding wires, while the blanks are moving along, mechanism for gaging or positioning the parts of the 95 blank before the said wires are applied, said mechanism comprising a spacing finger for engagement between the edges of adjacent sections of the blank, said spacing finger being automatically operated independently 100 of control, by any space in the materials ahead thereof, a movable member, and means for movably mounting said finger on said member, said finger having spacing and non-spacing positions on said member, 105 and said member having motion only in a horizontal plane, the said finger being returned to starting point along a path at one side of its path of forward movement, without interrupting the said feeding motion. 110
6. A wire bound box blank machine in which the blanks have a step-by-step forward feeding motion, comprising means for applying the parallel binding wires, while the blanks are moving along, mechanism for 115 gaging or positioning the parts of the blank before the said wires are applied, said mechanism comprising a movable member, which has motion only in a horizontal plane, and a spacing finger carried by and having spacing and non-spacing positions on said member, said spacing finger being automatically operated independently of control by any space in the materials ahead thereof, the said finger being returned to starting point along 120 a path at one side of its path of forward movement, without interrupting the said feeding motion, which spacing finger is right side up while traveling in either direc- 125 tion.

7. A wire bound box blank machine in which the blanks have a step-by-step forward feeding motion, comprising means for applying the parallel binding wires, while the blanks are moving along, mechanism for gaging or positioning the parts of the blanks before the said wires are applied, said mechanism comprising a spacing finger for engagement between the edges of adjacent sections of the same blank, a device for withdrawing the finger, and a cam for moving the finger into spacing position, the said finger being returned to starting point along a path at one side of its path of forward movement, without interrupting the said feeding motion. 70
8. A wire bound box blank machine in which the blanks have a step-by-step forward feeding motion, comprising means for applying the parallel binding wires, while the blanks are moving along, a cleat guide mechanism for gaging or positioning the parts of the blank before the said wires are applied, said mechanism comprising a member movable in opposite directions at one side of the guide, a spacing finger carried by and having spacing and non-spacing positions on said member, said finger adapted to engage between the edges of adjacent sections of the same blank, means for automatically moving said finger into spacing position, and means for automatically moving said finger into non-spacing position, the said finger being returned to starting point along a path at one side of its path of forward movement, without interrupting the said feeding motion. 75
9. A wire bound box blank machine in which the blanks have a step-by-step forward feeding motion, comprising means for applying the parallel binding wires, while the blanks are moving along, cleat guides, mechanism for gaging or positioning the parts of the blank before the said wires are applied, said mechanism comprising two members which are movable beside the guides, a spacing finger carried by and having spacing and non-spacing positions on each said member, a device individual to each finger for actuating it to one position, and a device to actuate the said finger to the other position, the said finger being returned to starting point along a path at one side of its path of forward movement, without interrupting the said feeding motion. 80
10. A wire bound box blank machine in which the blanks have a step-by-step forward feeding motion, comprising means for applying the parallel binding wires, while the blanks are moving along, mechanism for gaging or positioning the parts of the blank before the said wires are applied, said mechanism comprising a device for engagement between the edges of adjacent sections of the blank, said device being automatically operated independently of control by any space in the materials ahead thereof, a traveling member upon which said device has spacing and non-spacing positions, a cleat guide in the path of which said device travels while in engagement with the blank, the movement of the said device from one position to another on said member being in a direction transverse of the direction of said travel, and means for actuating the said device from one position to the other, the said device being returned to starting point along a path at one side of its path of forward movement, without interrupting the said feeding motion. 85
11. A wire bound box blank machine in which the blanks have a step-by-step forward feeding motion, comprising means for applying the parallel binding wires, while the blanks are moving along, mechanism for gaging or positioning the parts of the blank before the said wires are applied, said mechanism comprising spring actuated spacing fingers for engagement between the edges of adjacent sections of the blank, at opposite sides thereof, each finger movable in a direction transverse of the direction of travel of the work, and means for actuating said fingers against the spring tension thereof. 90
12. A wire bound box blank machine in which the blanks have a step-by-step forward feeding motion, comprising means for applying the parallel binding wires, while the blanks are moving along, mechanism for gaging or positioning the parts of the blank before the said wires are applied, said mechanism comprising cam-actuated and traveling spacing fingers for engagement between the edges of adjacent sections of the blank, said spacing fingers being automatically operated independently of control by any space in the materials ahead thereof, a support upon which each finger is movable relative thereto in a direction transverse of the direction of travel of the work, and means whereby each finger is returned to starting point along a path at one side of its path of forward movement, without interrupting the said feeding motion. 95
13. A wire bound box blank machine in which the blanks have a step-by-step forward feeding motion, comprising means for applying the parallel binding wires, while the blanks are moving along, parallel cleat guides, mechanism for gaging or positioning the parts of the blank before the said wires are applied, said mechanism comprising a plurality of fingers movable along each guide to space the different sections of the same blank, and traveling members upon which said fingers are movable to spacing and non-spacing positions, each finger movable in a direction transverse of the direction of travel of the work, each finger being returned to starting point along a path at 100
- 105
- 110
- 115
- 120
- 125
- 130

one side of the guide thereof, and means whereby said members are automatically operated in opposite directions.

14. A wire bound box blank machine in which the blanks have a step-by-step forward feeding motion, comprising means for applying the parallel binding wires, while the blanks are moving along, and mechanism for gaging or positioning the parts of the blank before the said wires are applied, said mechanism comprising a veneer spacing finger movable forward a distance with the blank and automatically operative independently of control by any space in the materials ahead thereof, and arranged to return at one side of its path of forward movement in close proximity to the blank, said finger being right side up while traveling in each direction.
15. A wire bound box blank machine in which the blanks have a step-by-step forward feeding motion, comprising means for applying the parallel binding wires, while the blanks are moving along, and mechanism for gaging or positioning the parts of the blank before the said wires are applied, said mechanism comprising movable means having spring controlled spacing fingers each movable forward a distance with the blank, automatically operative independently of control by any space in the materials ahead thereof, and arranged to return at one side of its path of forward movement, and in close proximity to the blank, said finger being right side up while traveling in each direction.

16. A wire bound box blank machine in which the blanks have a step-by-step forward feeding motion, comprising means for applying the parallel binding wires, while the blanks are moving along, mechanism for gaging or positioning the parts of the blank before the said wires are applied, said mechanism comprising a pair of endless chains provided with spacing devices, which chains are operable in the same horizontal plane, and means for depressing said devices whereby said devices do not strike the work while returning immediately below the blanks.

17. A wire bound box blank machine in which the blanks have a step-by-step forward feeding motion, comprising means for applying the parallel binding wires, while the blanks are moving along, mechanism for gaging or positioning the parts of the blank before the said wires are applied, said mechanism comprising parallel cleat guides, an endless link belt beside each guide, and spacers secured to the side of said belt and projecting laterally therefrom to slide along said guides, whereby the said spacers support the belts on the guides, said spacers adapted to engage between the ends of adjacent cleats of the blank, together with means

for automatically disengaging the spacers before the said belt changes its course of travel, and without changing the course of the blank.

18. A wire bound box blank machine comprising guides for the cleats, and spacing devices for positioning the veneer on the cleats, each device movable forward with the work to position the veneer, and each device movable backward along a path at one side of its path of forward travel, each device being right side up while traveling in both directions, movable means on which said devices have spacing and non-spacing positions, and mechanism whereby said spacing devices are automatically returned to starting position.

19. A wire bound box blank machine comprising guides for the cleats, spacing devices for positioning the veneer on the cleats, each device movable forward with the work to position the veneer, and each device movable backward along a path at one side of its path of forward travel, each device being right side up while traveling in both directions, a movable carrier for each device, each carrier having motion only in a horizontal plane, and mechanism whereby said spacing devices are automatically returned to starting position.

20. A wire bound box blank machine comprising parallel guides for the cleats, feed belts operating in horizontal planes, disposed between said guides, means having vertical axes for supporting said belts, said belts being engaged with the cleats, means for causing said belts to have a step by step movement, to feed the cleats along said guides, automatically operable fingers for spacing apart the edges of the veneer, and stapling mechanism for securing the binding wires in place.

21. A wire bound box blank machine comprising parallel guides for the cleats, feed belts operating in horizontal planes, disposed between said guides, means having vertical axes for supporting said belts, said belts being engaged with the cleats, means for causing said belts to have a step by step movement, to feed the cleats along said guides, automatically operable fingers for spacing apart the edges of the veneer, and stapling mechanism for securing the binding wires in place, and means for adjusting the distance between said guides and belts to change the width of the blanks.

22. A wire bound box blank machine comprising parallel guides for the cleats, feed belts operating in horizontal planes, disposed between said guides, means having vertical axes for supporting said belts, said belts being engaged with the cleats, means for causing said belts to have a step by step movement, to feed the cleats along said guides, automatically operable fingers for spacing apart the edges of the veneer, sta-

- pling mechanism for securing the binding wires in place, and means for adjusting the distance between said belts to change the width of the blanks, or to accommodate 5 cleats of different width in said guides.
23. A wire bound box blank machine comprising parallel guides for the cleats, feed belts operating in horizontal planes, disposed between said guides, means having 10 vertical axes for supporting said belts, said belts being engaged with the cleats, means for causing said belts to have a step by step movement, to feed the cleats along said guides, stapling mechanism for securing the 15 binding wires in place, spacing fingers for separating the edges of the veneer, said fingers being automatically operated independently of control by any space in the veneer ahead thereof, means for forcing said fingers into spacing position, and means for extracting the fingers from between said edges.
24. A wire bound box blank machine comprising parallel guides for the cleats, feed belts operating in horizontal planes, disposed between said guides, means having 25 vertical axes for supporting said belts, said belts being engaged with the cleats, means for causing said belts to have a step by step movement, to feed the cleats along said 30 guides, and stapling mechanism for securing the binding wires in place, spacing fingers for separating the edges of the veneer, said fingers being automatically operated independently of control by any space in 35 the veneer ahead thereof, means for forcing said fingers into spacing position, and means for extracting the fingers from between said edges, each finger having a support which has movement only in a horizontal plane.
- 40 25. A box blank machine comprising guides for the blank material, means for causing a step by step movement of the materials along said guides, spacing mechanism including a finger for separating the 45 edges of the veneer, said finger having an associated portion which enters between the ends of the cleats, to cause said finger to correctly position the edges of the veneer relative to the ends of the cleats, means for 50 actuating said finger into spacing position, means for withdrawing the finger from between the edges of the veneer, and stapling mechanism for applying the binding wires to the said materials.
- 55 26. A box blank machine comprising means for spacing the cleats apart endwise, means acting on the cleats to cause the blank materials to have a step by step forward movement, devices for spacing apart 60 the edges of the veneer, mechanism for wiring the materials together, and means for withdrawing said devices from between the said edges, to permit the said devices to return to normal position.
- 65 27. A wire bound box blank machine com- prising means for producing a step by step advancement of the blank materials, staplers for wiring the materials together, and mechanism for properly positioning the materials, before the wiring together thereof, 70 comprising a finger operable into and out of the path of said materials and movable a fixed distance therewith, whereby said finger has the same extent of motion for different lengths of blank, said finger engaging 75 between the edges of the veneer to space the same apart, and being automatically operated independently of control by any space in the veneer ahead thereof.
28. A wire bound box blank machine comprising means for producing a step by step advancement of the blank materials, staplers for wiring the materials together, mechanism for properly positioning the materials, before the wiring together thereof, 80 comprising a finger operable into and out of the path of said materials and movable a fixed distance therewith, whereby said finger has the same extent of motion for different lengths of blank, and means for moving said finger into operative position, said finger engaging the edges of the veneer to space the same apart, and being automatically operated independently of control by 85 any space in the veneer ahead thereof.
29. A wire bound box blank machine comprising means for producing a step by step advancement of the blank materials, staplers for wiring the materials together, mechanism for properly positioning the materials, before the wiring together thereof, 90 comprising a finger operable into and out of the path of said materials, movable a fixed distance therewith, whereby said finger has the same extent of motion for different lengths of blank, and means for forming the spaces between the ends of the cleats, said finger engaging between the edges of the veneer to space the same apart.
30. A wire bound box blank machine comprising means for producing a step by step advancement of the blank materials, staplers for wiring the materials together, mechanism for properly positioning the materials, before the wiring together thereof, 100 comprising a finger operable into and out of the path of said materials, movable a fixed distance therewith, whereby said finger has the same extent of motion for different lengths of blank, and separate means for forming the spaces between the ends of the cleats, said finger engaging between the edges of the veneer to space the same apart.
31. A wire bound box blank machine comprising a spacer automatically operated independently of control by any space in the materials ahead thereof, a movable member whereon said spacer has spacing and 110

- 125
- 130

- non-spacing positions relative thereto, means for automatically forcing said spacer into spacing position, means for automatically actuating said spacer to non-spacing position, means for movably supporting said member, feed mechanism whereby the materials have a step-by-step forward motion, and stapling devices for wiring the materials together. 75
- 10 32. A wire bound box blank machine comprising a spacer automatically operated independently of control by any space in the materials ahead thereof, a traveling member whereon said spacer has spacing and non-spacing positions relative thereto, means for automatically forcing said spacer into spacing position, means for automatically actuating said spacer to non-spacing position, means for movably supporting said member, feed mechanism whereby the materials have a step-by-step forward motion, and stapling devices for wiring the materials together, the said non-spacing position of said spacer being in a plane below the spacing position thereof. 80
- 15 33. A wire bound box blank machine comprising a spacer automatically operated independently of control by any space in the materials ahead thereof, a traveling member whereon said spacer has spacing and non-spacing positions relative thereto, means for automatically forcing said spacer into spacing position, means for automatically actuating said spacer to non-spacing position, means for movably supporting said member, feed mechanism whereby the materials have a step by step forward motion, and stapling devices for wiring the materials together, the said machine including 85 means for spacing between the ends of the cleats. 90
- 20 34. A machine for making wire bound box blanks by wiring together previously unconnected sections, there being separate cleats for each section, comprising means for guiding the cleats in parallel rows, cleat spacers having both forward and return movement in the common plane of said rows without interfering with the forward feeding motion of said materials, and mechanism for wiring the sections together. 95
- 25 35. A machine for making wire bound box blanks by wiring together previously unconnected sections, there being separate cleats for each section, comprising sheet spacers movable a distance with the sheets, between the edges thereof, means whereby each spacer travels forward along one path, and backward along another path at one side of said first path, devices for keeping said spacers depressed while returning below the sheets, and mechanism for wiring the sections together. 100
- 30 36. A machine for making wire bound box blanks by wiring together previously unconnected sections, there being separate cleats for each section, comprising sheet spacers movable a distance with the sheets, between the edges thereof, means whereby each spacer travels forward along one path, and backward along another path at one side of said first path, devices for keeping said spacers depressed while returning below the sheets, and mechanism for wiring the sections together, cleat guides, and spacers for separating the cleats endwise thereof. 105
- 35 37. A machine for making wire bound box blanks by wiring together previously unconnected sections, there being separate cleats for each section, comprising means for guiding the cleats in parallel rows, cleat spacers having both forward and return movement in the common plane of said rows, and mechanism for wiring the sections together, sheet spacers, and a ratchet feed mechanism for causing intermittent feeding motion of said spacers with the cleats and sheets. 110
- 40 38. A box blank machine for wiring together the previously unconnected sections of each blank, comprising cleat guides, and cleat spacers adjacent said guides in the common plane thereof, each said spacer being mounted for movement only in the common plane of the rows of cleats. 115
- 45 39. A wire bound box blank machine comprising a spacer automatically operated independently of control by any space in the materials ahead thereof, a traveling member whereon said spacer has spacing and non-spacing positions relative thereto, means for automatically forcing said spacer into spacing position, means for automatically actuating said spacer to non-spacing position, means for movably supporting said member, feed mechanism to give the materials a step by step forward motion, and stapling devices for wiring the materials together, the said machine including means for spacing between the ends of the cleats and for engaging the cleats to feed them along said guides. 120
- 50 40. A machine for making box blanks from sheets and cleats, comprising traveling means having elements held in fixed position thereon for spacing the cleats apart endwise, stationary members for engaging the sides of the cleats to prevent lateral displacement thereof, mechanism for wiring together the previously unconnected side sections of the blanks by successive operations thereon, and devices for actuating said means and thereby feeding the sheets and cleats to said mechanism, said means including link belts arranged to operate in a horizontal plane, and sprockets for said belts having vertical axes of rotation. 125
- 55 41. A machine for making foldable box blanks from sheets and cleats, comprising a plurality of endless link belts, blocks se- 130

cured to said belts in fixed relation to space the cleats of each blank, stationary means to hold the cleats between said blocks and in parallel rows, staplers for wiring together the previously unconnected sections of each blank, by a plurality of successive stapling operations thereon, and mechanism for actuating said belts a plurality of times for each blank to feed the materials into position for stapling, said belts arranged

to operate said blocks in one and the same common plane throughout the course of travel thereof.

Signed by me at Chicago, Illinois, this 30th day of September, 1911.

JULIUS J. MILLER.
